GOLF PRACTICING MACHINE

Kate Marion Lawson, Surbiton, England

Application February 12, 1934, Serial No. 710,921
In Great Britain February 15, 1933

5 Claims. (Cl. 273—35)

This invention relates to golf-practicing appliances of the kind in which a golf ball is arranged when struck to rotate with or about a horizontal spindle. If the ball is fixed to one end of an arm carried by the spindle and the spindle carries a counterbalance weight or arm, the appliance is of very little practical value, because the effect is that of striking a dead weight several times the actual weight of a golf ball.

10 The primary object of the invention is to provide an appliance in which conditions much more closely approximating to those encountered in actual play are produced. A further object is to provide a cheap but robust appliance, part of which may be sunk permanently into the ground while the other part may easily be placed in position when the appliance is to be used.

In appliances according to the invention the ball is mounted on a helical spring which rotates 20 with or about a spindle. Such a spring, however, tends to swing to one side or the other if the ball is not truly struck, and according to the invention the ball and spring are constrained to rotate in a plane perpendicular to the axis of the spindle. This is preferably effected by providing two guide rings between which a collar or the like at the end of the spring moves.

The complete appliance preferably comprises a casing adapted to be sunk into the ground and 30 having a detachable cover which is very slightly raised from the ground when placed in position on the casing. This cover may then carry the spindle in a depending bracket, so that by removing the cover all the operative parts are also 35 removed and can be stored in a dry place when not in use. The cover may advantageously be provided with a rubber or other soft or resilient covering, so as to prevent damage to the club such as would occur if the cover were struck instead 40 of the ball.

In order that the invention may be clearly understood and readily carried into effect, one appliance constructed in accordance therewith will now be described by way of example with reference to the accompanying drawing in which Figure 1 shows a longitudinal section through and Figure 2 shows a plan of the appliance.

The appliance comprises a semi-cylindrical casting 1 adapted to be sunk in the ground and having 50 an opening 2 at the bottom to permit rain water to escape. The casing is closed by a cover 3 having two depending brackets 4. Each of these is circular and has four radial arms 5. The centre of each bracket contains ball bearings 6 in which 55 runs a spindle 7 carrying a rectangular plate 8.

This plate serves as a seating and point of attachment for a helical spring 9 and a balance weight 10. At the top of the helical spring is fixed a collar 11, which also serves as a socket into which a solid rubber ball 12 is fixed by means of a counter-sunk cap 13 that screws over a spindle passing upwards through the socket 11 and ball 12. The circular arms 14 of the bracket 4 constitute guides between which the collar 11 moves.

The cover 3 is formed with an opening 15 so as to allow the ball 12 and spring 9 to rotate freely with the spindle 7. The cover is also provided with a rubber covering 16, so that if the ball should not be truly struck the club will not be damaged by coming into contact with the metal part of the cover.

In some instances an indicator may be provided to show the distance which the ball would have travelled if it had been played on the golf course in the usual way. An indicator in the form of a revolution counter is shown in Figures 1 and 2 at 17, this indicator including a star wheel 18 engaged by a pin 19 projecting from the collar 11. It will of course be clear that any suitable form of indicator may be used, and that when a revolution counter is used, it may be of the type that will re-set itself to the zero position on the movement of a push button or the like.

I claim:

1. In a golf-practicing appliance, the combination of a helical spring means mounting the spring for rotation about an axis perpendicular to the spring axis, a ball carried by said spring and means other than the mounting means for constraining said ball and spring to rotate substantially in a plane perpendicular to the axis of rotation.

2. In a golf-practicing appliance, the combination of a spindle, a helical spring mounted thereon and extending radially therefrom, a ball carried by said spring, and means other than the spindle for constraining said ball and spring to rotate in a plane substantially perpendicular to the axis of said spindle.

3. In a golf-practicing appliance, the combination of a helical spring mounted on and rotatable about a shaft whose axis is perpendicular to the spring axis, a ball carried by said spring, and guide rings arranged to co-operate with said spring and to constrain said spring and ball to rotate substantially in a plane perpendicular to the shaft.

4. In a golf-practicing appliance, the combination of a casing adapted to be sunk into the ground, a cover for said casing, said cover being formed with an opening, a bracket depending 5 therefrom into said casing, a spindle carried by said casing, a helical spring mounted on and extending radially from said spindle, a ball carried by said spring and normally projecting through the opening in said cover, and means

other than the spindle for constraining said ball and spring to rotate in a plane substantially perpendicular to the axis of said spindle.

5. In a golf-practicing appliance, the combination claimed in claim 4, wherein said constraining means comprises two guide rings arranged to co-operate with said spring. 80
